ELECTRIC SWITCH BODY

William A. Rasor, Garden City, Mich., assignor to Gemco Electric Co., Detroit, Mich., a corporation of Michigan

Filed Feb. 25, 1963, Ser. No. 73,685

Term of patent 14 years

(Cl. D26—13)

FIG. 1 is a perspective view of the electric switch body showing my new design;

FIG. 2 is a top elevational view thereof;

FIG. 3 is a side elevational view thereof;

FIG. 4 is a bottom elevational view thereof;

FIG. 5 is a left-hand end elevational view thereof; and

FIG. 6 is a right-hand end elevational view thereof.

I claim:

The ornamental design for an electric switch body, substantially as shown.
